PRESSURE REGULATOR

Rasselas M. Decker, Anderson, Ind., assignor of
one-half to Fred M. Decker, Anderson, Ind.

Application January 6, 1930. Serial No. 418,927

2 Claims. (Cl. 50—22)

This invention appertains to improvements in pressure regulators generally, and has for its main object to provide an extremely simple but durable and efficient construction and arrangement of parts, wherein the automatic actuating means for the pressure controlled valve will operate with greater smoothness and much less strain under sudden and otherwise wide variations in pressures than has heretofore been the case in known types of automatic regulators.

Another object of the invention resides in the provision of an actuating means for automatic pressure regulator valves which is cushioned in its operative movements by the cooperation there-with of a body of liquid to obtain the desired smoothness of operation and freedom from strains as aforesaid without in any way affecting the required responsiveness thereof to variations of pressure.

20 A further object of the invention is to provide an actuating means for the control valve of a pressure regulator which will operate with a greater freedom from necessity of attention, adjustment and repair and with greatly increased smoothness aforesaid than the presently known type of regulators and more particularly the diaphragm types of such devices.

With the foregoing and other equally important objects and advantages in view, the invention resides in the certain new and useful combination, construction and arrangement of parts as will be hereinafter more fully described, set forth in the appended claims, and illustrated in the accompanying drawing, in which:

35 Figure 1 is a vertical section through a practical embodiment of the invention;

Figure 2 is a horizontal section, taken on the line 2—2 of Figure 1, and

Figure 3 is a side elevation of the upper end portion of the regulator and showing a modified form of the adjustable control means.

Referring to the drawing, the embodiment of the invention, as shown therein by way of example, is constituted in a lower casing part 10 which is normally open at its upper side and has outwardly bossed and interiorly screw threaded openings 11 and 12 in its opposite ends for the engagement therein of the adjacent and complementary screw threaded ends of a pressure intake pipe 13 and an outlet pipe 14 respectively.

Extending transversely of the interior of this casing part 10 is a partition 15 which has its top edge portion 15' extending angularly and connected with the top edge of the casing part at the intake end thereof. Projecting forwardly from

an opening at the center of the partition 15 toward the outlet end of the casing part, is a chamber 16 having upper and lower horizontal wall portions in which aligned openings are formed.

The upper edge of this casing part 10 is formed to provide an outturned flange 17 on which a top wall or division plate 18 and an upper casing part 10' are secured in super-imposed relation by means of suitable fastenings or bolts 19; the edge of the lower open side of the upper casing part 10' being likewise outwardly flanged, as at 17'. The body portion of the upper casing part 10' is preferably of an exterior and interior diameter equal to that of the lower casing part 10, so that the casing in its entirety is generally of cylindrical form when set up and ready for use.

An opening is formed centrally of the division plate 18, in line with the centers of the openings in the top and bottom walls of the chamber 16, and a second opening is provided in the top wall of the upper casing part 10' in line with the other of said openings in order to receive therethrough a valve stem formed of a lower portion 20 and an upper portion 20', the latter being preferably of a lesser diameter than the former substantially as shown. Surrounding the stem portion 20 at the upper side of the division plate 18 is a stuffing box 21 to prevent escape or seepage of pressure or liquid from one casing part to the other.

The lower end of the upper stem portion 20' is preferably screw threaded upwardly from the point of connection with the upper end of the lower stem section 20, and engaged over the same, between the latter and an adjustable clamp nut 22, is a piston which is made up of a lower metal plate 23, an intermediate flexible disk 24 and an upper metal plate 25. These plates 23 and 25 and the disk 24 are of circular form to correspond to the preferred cylindrical form of the casing parts 10 and 10', the upper plate 25 is of a diameter so as to have a snug sliding fit in the casing part 10'; the intermediate disk 24, which is preferably of leather, of a greater diameter in order to have its marginal edge cupped in a downward direction to bear against the side wall of the casing part 10'; and the lower plate 23 of a slightly less diameter than the upper plate 25 in order to have its peripheral edge to engage at the inner side of the depending flange portion of the cupped portion of the disk 24. Disposed on the lower side of the lowermost plate 23 is an annular member or ring 26 having a channel in its outer side face to receive a spring member 27 which bears against the inner side 110

of the cupped marginal edge portion of the disk 24 to tension the same against the opposed wall of the casing part 10'.

Arranged in circular series in the piston 23 and concentrically about the valve stem section 20' are a number of openings 28 which extend vertically through both of the plates 23 and 25 and the intermediate disk 24 to establish communication between the chambers formed above and below the piston and to permit oil or the like, supplied to the lower of the chambers by a piped inlet 29, to pass from the latter to the upper chamber, as occasion requires.

Secured on the upper side of the top plate 25 of the piston 23, in concentric relation about the valve stem section 20' and the openings 28, is a cylindrical body or cup 30, which has its lower end open and its side wall outwardly flanged to permit fastening thereof to the plate 25 of the piston by means of bolts or the like 31. This body or cup 30 is of a height and diameter to give to the same an appreciable capacity for the reception therein of the amount of the oil to pass to the same upwardly through the openings 28 during certain of the operative movements of the valve stem, but its height is such that it will be free from contacting relation with the top wall of the upper casing part 10' when the valve stem moves to its uppermost position. The top wall 30 of the inverted cup 30 has a central opening therein to engage over the threaded portion of the upper stem 20' and is clamped between two nuts 32 and 32'.

Formed with or mounted on the lower end of the valve stem section 20 is a valve body 33 arranged to engage a seat 34 removably secured in the opening aforesaid formed in the top wall of the pressure chamber 16, while a second valve body 35 is formed with or mounted on a separate valve stem section 20'' which is dependently supported from the center of the lower side upper valve body 33. This lower valve body 35 is arranged to seat in the hereinbefore mentioned opening in the bottom wall of the pressure chamber 16. Thus both of these valves 33 and 35 open and close on their respective seats simultaneously whenever the valve stem is actuated as will be hereinafter more fully explained. The valve seat 34 is preferably screw threaded into the upper opening of the chamber 16 and thereafter further secured in place by means of a bolt 34'.

The upper end of the valve stem section 20' projects through the opening in the top wall of the casing part 10' to a sufficient amount to receive on the same a length of coiled spring 36, which is adjustably tensioned in place by means of a washer 37 and a nut 38, the latter being arranged in screw threaded engagement on the free end portion of the stem section 20'. A stuffing box 39 is provided on the upper side of the top wall of the casing part 10' and about the projecting end portion of the stem section 20' and the lower end of the spring 36 bears against the top end of the adjustable packing nut 39'.

In the operation of the regulator as thus constructed and arranged, the spring 36 normally functions to maintain the balance valves 33 and 35 open, in which condition, the piston 23 is elevated in the casing part 10', so that pressure from the inlet 13 will pass directly through the casing part 10 and the chamber 16, to the outlet 14; a portion of the pressure, from the lower pressure or outlet side of the casing part 10 being lead by a pipe connection 40 to the upper casing part 10' at a point above the piston 23. This pipe con-

nection 40 as shown, is preferably connected to the outlet pipe 14 immediately adjacent the point of connection of the same with the adjacent side of the casing part 10 and enters the upper casing part 10' at the same side thereof well toward its upper end.

Now, with the chamber in the lower side of the upper casing part 10' filled with oil from the supply pipe or inlet 29, and the valves 33 and 35 sustained in open position by the action of the spring 36, the tensioning effect of the latter will be opposed by the pressure admitted to the upper chamber of the casing part 10', through the pipe 40 from the main pressure outlet 14, acting on the upper side of the piston 23 to the end that the valves will be regulated thereby to the desired gage pressure to be maintained in the system. In the event of an increase of pressure above the gage pressure setting of the spring 36, a downward movement of the piston 23 occurs by the effect of the increased pressure on its upper side, and the valves will be correspondingly moved toward closed position. This downward movement of the piston 23 is, however, obtained only with a slight retardation effect from the body of oil in the lower chamber but also with an accompanying gradual upflow of the oil through the openings 28 and into the cup 30. Also in such movement, the spring 36 will of course be correspondingly compressed.

In the event that the demand for pressure on the outlet 14 increases, the pressure in the chamber of the upper casing part 10' above the piston 23 will be lowered, when the spring 36 will expand in a corresponding amount and increase the opening of the valves 33 and 35 by lifting the valve stem and the piston 23, so that a proper additional amount of pressure will pass through the lower casing part 10 from the inlet 13 to the outlet 14. As the piston 23 rises, in this instance of its operation, the oil which had previously entered the cup 30 will be forced back into the space or chamber below the piston.

As shown in Figure 1, the outer end of the oil inlet 29 terminates in a flattened hollow portion 41, which has an opening in its upper side in communication with the bore of a sight tube 42. The upper end of the sight tube 42 is disposed in registry with an opening formed in the open side of a similar hollow flattened portion 43 of a piped pressure outlet 44 opening into the casing part 10' at a point above the piston 23. The oil inlet 29 and the pressure outlet 44 are provided with cutoff valves 45 and 46 respectively, which are located outwardly of the casing part 10' and between the same and the sight tube 42. Thus, the body of oil in the lower chamber of the upper casing part 10' and the sight tube 42 may be subjected to pressure in the upper chamber when the valves 45 and 46 are open.

A suitable oil supply (not shown) will be connected to the upper side of the upper flattened portion 43 by means of the connection 47, which is provided for the purpose and which opens into the portion 43 at the outer side of the cutoff valve 46 for the passage of oil directly to the sight tube. A cutoff valve 48' will also be provided in the pipe connection 40 to control the pressure admitted to the upper chamber in the upper casing part 10' from the pressure outlet 14.

In Figure 3, a control lever 49 is substituted for the adjustable tension spring 36 and here, the valve stem 20' is pivoted in the forked end 49' of the lever which is, in turn, pivoted at an intermediate point 50 in the upper forked end of a 150

bracket 51 rising from the top wall of the casing part 10'. An adjustable weight 52 is slidably mounted on the free end portion of the lever 49. Thus, by moving the weight along the lever 49, 5 the regulator may be said to operate at any desired pressure.

Without further description, it is thought that the features and advantages of the invention will be readily apparent to those skilled in the art, 10 and it will of course be understood that changes in the form, proportion and minor details of construction may be resorted to, without departing from the spirit of the invention or its scope as claimed.

15 I claim:

1. In a pressure regulator, a casing formed to provide upper and lower compartments, the said lower compartment having an inlet and an outlet for the pressure, a valve in said lower compartment for regulating the flow of pressure therethrough, a rigid partition between said upper and lower compartments, a stem passing from said valve and upwardly through said partition, a piston mounted on said valve stem within said 25 upper compartment and dividing said compartment into independent chambers, means for introducing pressure from the outlet side of said casing into the said upper chamber above said piston, spring means acting on said valve stem 30 to elevate the same and associated parts against the force of pressure at the upper side of the piston, and a relatively non-compressible fluid with-

in said chambers adapted to be displaced alternately upon opposite sides of said piston as the size of the chambers vary according to movements of said piston.

2. In a pressure regulator, a casing formed to provide upper and lower compartments, the said lower compartment having an inlet and an outlet for the pressure, a valve in said lower compartment for regulating the flow of pressure therethrough, a rigid partition between said upper and lower compartment, a stem passing from said valve and upwardly through said partition and said upper compartment, a piston carried on said valve stem within said upper compartment and dividing said compartment into independent upper and lower chambers, means for introducing pressure from the outlet side of said casing into said upper compartment above said piston, spring means acting to elevate the valve stem, the piston and the valve against the force 95 of the pressure at the upper side of the piston, said valve being open in the elevated position thereof, a cup-shaped member carried at the upper side of said piston, said piston having openings to establish communication between 100 said cup and the said lower chamber, and fluid means within said lower chamber and adapted to be displaced upwardly through the said openings, and into said cup upon any downward movement of said piston due to increased variations in pressure on the upper side of the same. 105
